[57] CLAIM

The ornamental design for a face panel for an online bar code card reader, as shown and described.

DESCRIPTION

FIG. 1 is a perspective view of a face panel for an online bar code card reader showing our new design;
FIG. 2 is a top plan view thereof;
FIG. 3 is a front elevation view thereof;
FIG. 4 is a back elevation view thereof;
FIG. 5 is a right side elevation view thereof;
FIG. 6 is a left side elevation view thereof; and,
FIG. 7 is a bottom plan view thereof.

The broken-line drawing of a rear panel in FIGS. 1, 2, 5, 6, and 7 is for illustrative purposes only and forms no part of the claimed design.
